(57) **CLAIM**

We claim the ornamental design for a computer, as shown and described.

DESCRIPTION

FIG. 1 is a front perspective view of a computer with a display in a closed position;

FIG. 2 is a left side elevational view of the computer of FIG. 1;

FIG. 3 is a right side elevational view of the computer of FIG. 1;

FIG. 4 is a top plan view of the computer of FIG. 1;

FIG. 5 is a front elevational view of the computer of FIG. 1; FIG. 6 is a rear elevational view of the computer of FIG. 1; FIG. 7 is an enlarged fragmentary left side elevational view of the computer of FIG. 1;

FIG. 8 is an enlarged fragmentary sectional view of the computer of FIG. 7 taken along lines 8-8;

FIG. 9 is a fragmentary sectional view of the computer of FIG. 7 taken along lines 9-9;

FIG. 10 is a front perspective view of the computer of FIG. 1 with the display in an opened position;

FIG. 11 is a left side elevational view of the computer of FIG. 10;

FIG. 12 is a right side elevational view of the computer of FIG. 10;

FIG. 13 is a top plan view of the computer of FIG. 10;

FIG. 14 is a front elevational view of the computer of FIG. 10; FIG. 15 is a rear elevational view of the computer of FIG. 10; and,

FIG. 16 is an enlarged fragmentary left side elevational view of the computer of FIG. 10.

The dash-dash broken lines in the drawings are environmental lines which do not form part of the claimed design.
